(57) **CLAIM**

The ornamental design of the key chain oval ornament with pivoting disc, as shown and described.

DESCRIPTION

FIG. 1 is a plan view of the key chain oval ornament with pivoting disc design;

FIG. 2 is a side view of FIG. 1, both sides being identical; FIG. 3 is a top view of FIG. 1;

FIG. 4 is a bottom view of FIG. 1;

FIG. 5 is a perspective view of FIG. 1;

FIG. 6 is a side view of a key chain oval ornament with pivoting disc showing a second embodiment of my new design.

FIG. 7 is a side view of FIG. 6, both sides being identical;

FIG. 8 is a top view of FIG. 6;

FIG. 9 is a bottom view of FIG. 8; and,

FIG. 10 is a perspective view of FIG. 6.
